Primary Examiner — Garth Rademaker*Assistant Examiner* — Katelin G Kloberg(74) *Attorney, Agent, or Firm* — Renner Kenner Greive Bobak Taylor and Weber; Tim Hodgkiss(57) **CLAIM**

The ornamental design for a weighted vest for dogs, as shown and described.

DESCRIPTION

FIG. 1 is a top front perspective view of the weighted vest for dogs showing my new design;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.

The broken lines shown in the drawings illustrate portions of the weighted vest for dogs that form no part of the claimed design.

1 Claim, 4 Drawing Sheets(56)
